UNITED STATES PATENT OFFICE.

CARL M. HUGULEY, OF DALLAS, TEXAS.

AUTOMATIC MACHINE FOR MANUFACTURING MOPS.

1,201,965.

Specification of Letters Patent. Patented Oct. 17, 1916.

Application filed July 6, 1916. Serial No. 107,849.

To all whom it may concern:

Be it known that I, CARL M. HUGULEY, a citizen of the United States of America, residing at Dallas, in the county of Dallas, 5 State of Texas, have invented certain new and useful Improvements in Automatic Machines for Manufacturing Mops, of which the following is a specification.

This invention relates to a new form and 10 design of automatic machines adapted for use in connection with the manufacturing of mops.

In the manufacture of household and general utility mops the yarn pack or strands 15 composing the mop proper are secured to a staff or handle by various means.

In the present invention conceived in the automatic machine herewith illustrated, the said invention appertains to a particular 20 form of automatic machine for operation in connection with a certain form of mop-head device, which device is known as a mop ferrule.

The ferrule illustrated in the drawings is 25 adapted to secure the yarn pack or mop strands to the handle of the mop and has been heretofore made the subject matter of a patent separate and distinct from the present invention.

30 A purpose of the present invention is to design and provide a machine automatic in operation for packing yarn or strands in the ferrule, securely closing the parts of the ferrule or arms down over and around 35 the strands. The ferrule combined with the strands or yarn pack, the combination of which may be known as the mop-head, is then removed from the machine, after which a new ferrule is placed therein and 40 arranged to receive the next yarn pack.

A further purpose of the invention is to 45 design and provide such a machine as will be composed of a plurality of closing dies mounted upon and carried by operating arms, adapted to close and punch down the ferrule arms or tabs in position around the yarn.

50 A further purpose of the invention is to provide such a machine as will be simple and efficient in operation and construction.

With the above and further objects in view the invention has relation to a certain combination and assembly of parts and ele-

ments as hereinafter described in this specification, pointed out in the appended claims 55 and illustrated in the accompanying drawings, wherein:

Figure 1 illustrates the machine in side elevation. Fig. 2 shows the machine in rear elevation. Fig. 3 shows the machine in 60 front elevation. Fig. 4 shows a portion of the machine in side sectional elevation and illustrated in connection with the ferrule heretofore mentioned. Fig. 5 illustrates the upper portion of the machine in side 65 sectional elevation and shows the several closing dies in a certain operative position. Fig. 6 is a plan view of a portion of the upper part of the machine. Fig. 7 is a perspective view of the ferrule shown in closed 70 position with the several closing dies in various positions. Fig. 8 illustrates in perspective the ferrule used in connection with the mop which the present automatic machine is adapted to manufacture. Fig. 9 75 shows a mop as completed by the machine. Fig. 10 illustrates in plan view a certain bifurcated packing arm used in connection with this invention. Fig. 11 is a view taken upon the section line 5—5 of Fig. 5. Fig. 80 12 is a partial view in front sectional elevation of a portion of the operating mechanism, showing several of said operating parts in a closing contacted relationship with the mop ferrule. 85

Referring now more in particular to the drawings, wherein the same reference characters are used to designate identical parts throughout the views, and wherein the ferrule construction will be referred to, the 90 character *a* indicates the cylindrical body of the ferrule which body has formed thereon, one diametrically opposite the other, arms or tabs *b* and *c*. The arm *c* has integrally formed therewith projecting ears *d*. The 95 arm *b* has a substantial length which provides an extended tab *e* formed on the extremity thereof, which is adapted to be turned or punched upwardly in a position as indicated in dotted lines in Fig. 8. Fig. 8 100 of the illustrations show the ferrule and the results of its shape and form after the machine has effectively closed the tabs of said ferrule upon the yarn or mop strands, but for clearness, shown in said view without said strands. In the manufacture of the 105

ferrules previously to placing them in position in the machine the said ferrule arms extend from the body *a* in a parallel position.

5 Referring now in particular to the several views illustrating the machine, the numeral 1 points out the body or base of the machine upon which base is assembled the automatic mechanism. The base of the machine will 10 preferably have a shape and form as illustrated, with a substantially large base and of a height convenient for an attendant or operator. The base of the machine upon its upper extremity has integrally formed 15 therewith a table surface 2. Lugs 3 integrally formed with the base project from the sides thereof and support a pair of vertical brackets 4. Bearings 5 are integrally formed upon the upper extremities of the 20 brackets and are adapted to journal and support a shaft 6. A shaft 7 is journaled in bearings 8 which are integrally formed on the lower portion of the members 4. A driving wheel 9 is carried upon the shaft 7 25 and adapted to drive the machine from power applied thereto. The wheel is substantially heavy in construction and has a substantial diameter which gives the power wheel sufficient inertia and momentum to 30 positively drive the various mechanisms.

A depending arm 11 is journaled upon the extremity of the shaft 6 projecting from one of the bearings 5. Said arm is provided with a pin 12 fixed in its lower extremity 35 which pin has connection with an arm member 13, which member extends forward and is formed to have its extremity in position near the center of the front face of the base. The pin 12 has connection with and 40 passes through an elongated slot 14 formed in the arm 13. A collar or nut 15 is carried by the pin and in rigid contact with the arm which prevents the pin from playing in or sliding along the slot, and insures 45 a united and connected movement of the two members 11 and 13. An upright oscillating member 16 is provided upon the side of the base as indicated by numeral 17 and extends vertically upward where the upper extremity of the said member 16 is provided 50 with a head 18. The forward extremity of the arm member 13 has a pivotal connection with the member 16 as indicated by the numeral 19 which designates a journal pin 55 connection between the two members. A tension spring 20 has one extremity fixed to the base and one extremity fixed to the member 13, which spring is adapted to restrain the correlated members 13 and 16 60 to an outwardly limited position as illustrated in Fig. 1.

A bifurcated packer member formed of an arm 21 is journaled upon the shaft 6 and has an extended arm 22 projecting rearwardly of the machine, the said packer 65

member having its forward extremity provided with extended integral furcations 23, which furcations have a form and contour as shown in the several side elevations of the drawings. The packer member as described is further illustrated in plan view in Fig. 10. A pivotal yoke member 70 consisting of parallel arms 24, which arms are provided with journals, is journaled upon the shaft 6. An extended arm 25 is integrally formed with the yoke member and extends forward of the machine where its extremity has a position approximately above the furcations of the packer arm. An arm 26 integrally formed with one of the 75 hub journals carrying one of the arms 24 is integrally formed with the said hub journal and extends rearwardly of the machine. A pivotal arm member composed of arms 27 and 28 is journaled upon the shaft 6. 80 The arm 27 has integral connection with the hub journal and extends forward in such a contour and form as to terminate its extremity approximately above the furcations of the packer arm. The arm 28 extends rearwardly of the machine. Another pivotal arm composed of arms 29 and 30 85 extending from a common hub journal is journaled upon the shaft 6.

The several pivotal arms as described are 90 all journaled independently one of the other upon the shaft and have their forward extremities so shaped in curvilinear form as to bring their forward extremities approximately over the center of the table of the 95 machine and above the furcations or head of the packer arm, this close association of the forward extremities of the several said arms being so arranged as to admit of and allow a free passage of each arm by the other 100 arm without interference or contact one with the other during the reciprocatory movement of each arm one by the other, which movement and operation will be brought out as the description of the invention is further 105 developed. The rear arms extended from the hub bearings of the several arms described are all provided upon their extremities with rollers 31, which rollers are journaled upon the side thereof. A roller 31 is 110 also carried by the rear extremity of the member 13 and journaled upon the pin 12. The rear or lower arms have substantially 115 the same or a similar length one with the other and all terminate at the rear of the machine in a position best calculated to assume an operative relation with elements hereinafter described. The packer member and adjacent pivotal arm members are journaled upon the shaft and confined between 120 the yoke member 24. Several cams 32, 32^a, 32^b, 32^c and 32^d, as illustrated, are mounted upon the shaft 7 in a fixed relationship thereto and adapted to be carried in revolution with the shaft 7. The four cams posi- 125 130

tioned upon the shaft 7 at the rear of the machine are each arranged upon the shaft 7 in alined operative contact with the afore-
 5 said rollers 31. A cam 32 located adjacent to the power wheel is also fixed to the shaft 7 and adapted to run in contact with the roller 31 carried by the depending arm 11. The cams vary each in size and circumferential contour one from the other, which difference in dimensions and shape is necessitated by the different actions in pivotal motion to be imparted to the various arms which are adapted to be operated and driven by the revolution of the several cams running in contact with the rollers of the respective arms.

The cams are provided with hubs, which hubs will be preferably provided with set-screws to set and fix the cams individually 20 one from the other to the shaft 7. It will later be seen how the several arms as described are required to pivotally operate synchronically one with the other; and to properly secure the results of synchronism 25 between the several arms it will be necessary in assembling the several cams upon the shaft 7 to place them thereupon and carefully work out the period of movement for each individual arm and set the set-screw 30 of each individual cam against the shaft 7.

Fig. 1 illustrates in elevation in solid and dotted line construction several of the cams, and in particular the cams adapted to operate the arms 11 and 26. The other arms have 35 a circumferential contour not dissimilar in form to the one shown in Fig. 1, the sizes of the various cams varying in diameter to suit the conditions of the required movement of the several arms.

40 A punch or turning die 33 is carried in the head 18 of the member 16 and pivoted in a slot formed therein, as shown in Fig. 4, upon a pin 34. The slot formed in the head 18 of the member 16 is slightly larger than 45 the width of the turning die which admits of said turning die or punch to have a slight pivotal action therein. A coil tension spring 34^a has connection with the die 33 and is adapted to restrict said die in a downwardly 50 limited position. Referring in particular to Figs. 4, 11 and 12 the numeral 35 designates a double or furcated die carried by and fixed to the arm 25. A closing die 36 is carried upon and fixed to the arm 27. A closing 55 die 37 is also fixed to and carried by the arm 29.

Closing dies 36 and 37 are alined one with the other and have their adjacent edges formed on an arc the circumference of which 60 is generated from the shaft 6. This allows the adjacent closing dies 36 and 37 to be alined one with the other and run in close relationship without any interference or contact one with the other, as seen in Figs. 11 and 12. The furcations of the bradding die

35 straddle the closing dies 36 and 37 confining them in the space between the prongs or furcations of said die. The edges of the die 35 are also formed on an arc generated from shaft 6. The extremities of the dies 70 35, 36 and 37 all have a form, shape and contour round in form, or nearly so, adapted to conform to the surface of the cylindrical form of the ferrule after the arms of said ferrule are closed. The lower extremities of the several die members are so arranged as to cause them to lie in a position adjacent to and alined with the underneath surface of the packer member when the dies 75 are in their downwardly limited position. 80

A pair of support guide members 38, which members are substantially triangular in form, and which members are integrally formed upon a rectangular surface base 39, are disposed upon the table surface of the 85 base and rise to a height substantially equal to the height of the ferrule when said ferrule has its arms extended and not folded over in position against the yarn pack. The said members have their adjacent surfaces 90 substantially vertical and parallel and of a distance apart adapted to receive a ferrule as shown in the illustrations. The tabs or arms of the ferrule where they join the cylindrical body bulge or slightly overhang the cylindrical body of the ferrule. The shape and form of the adjacent vertical surfaces of the members 38 are adapted to accommodate the contour of the ferrule, the arms or tabs and body of the ferrule being adapted to lie in contact with and be supported by the contacting surface of the member 38. A cylindrical pillar-post 40 integrally formed on a rectangular base 41 is accommodated in an opening 42 formed 105 in the table surface 2 of the base and securely fixed to the base 39 of members 38, which base 39 is securely fixed upon the table 2. The pillar-post 40 is of a cylindrical size sufficient to receive the cylindrical body 110 of the ferrule, said ferrule being positioned upon the pillar-post and having its lower edges in contact and supported upon the base 41. Slotted openings 43 are formed in the upper portions of the members 38 and 115 extend downwardly to a position substantially in line with the center of the yarn pack to be placed in the ferrule. The slots 43 formed in said members 38 are vertically alined with the several closing and 120 bradding dies and are of sufficient width to admit a free passage of the said dies down thereinto. The turning die 33 assumes a normal inoperative position, as illustrated in Fig. 4, where its working extremity lies 125 confined within the walls forming the slot 43 in one of the members 38. The working extremity of the die 33 is formed substantially as shown with a point formed by a surface having substantially a large diam- 130

eter. The furcations of the packer member are positioned apart with sufficient space therebetween to allow said furcations to freely pass down, over and along the edges 5 of the support guide members.

The attendant or operator of the machine will place a ferrule down in between the support guide members 38 and upon the pillar-post when all the arms and dies are 10 in an upwardly limited position. When the ferrule is placed in the position as described the ferrule tabs extend from the ferrule body in a parallel relation. Fig. 5 illustrates ferrule tabs in their extended and 15 unfolded position, which tabs lie in contact with the surface of the members 43 as shown in dotted line construction. The ears *d* formed on the tab *c* and which ears *d* formed thereon extend from the arm *c* in 20 parallel relation, are adapted to lap back in contact with the side surfaces of member 43, as shown in Figs. 5 and 6. Fig. 6 shows in a plan view the ferrule placed in position with the tabs resting in contact with the 25 vertical walls of the support member and shows how the ears *d* receive therebetween one of the members 38.

In the operation of the machine the attendant will place the ferrule in position as 30 heretofore described, and while the arms, closing dies, packer member and punch or turning die are all in their upwardly and outwardly limited position away from the ferrule and support guide members the attendant operator will place in position the 35 yarn or strand pack, quickly thrusting same down in between the jaws of the members 38 and into the open arms of the ferrule. At this time the power wheel in its continual revolution and with its internal 40 clutch mechanism will engage the shaft 7 and carry same forward for a complete turn, which action causes packer member and the various dies to be brought into 45 working contact with the ferrule, causing the tabs of said ferrule to be tightly closed around the strand pack placed therein, a further description in detail of the movement of said dies synchronically one with 50 the other is as follows. At the time the power wheel engages shaft 7 carrying the same forward the cam driven packer arm immediately causes said packer head to travel down and in firm contact with the 55 strand pack in the ferrule, which action packs the yarn or strands in a tight position and in a position cylindrical in cross section as illustrated. It is seen that the underneath surface of the packer member has a 60 jaw like formation which terminates in a cylindrical form, having a diameter substantially the same as the diameter of the closed arms of the ferrule. This causes the strand pack to assume a shape cylindrical 65 in cross section as heretofore mentioned. At

this time the arm 27 carrying the die 36 immediately starts downwardly, the closing die 36 descends into the slot formed in the member 38 and in contact with the upstanding tab *c* of the ferrule. The arcuate form 70 of the working end of the die 36 causes the tab *c* to be backwardly curved under the descending pressure of said die until the tab *c* is curled and pressed around the strand pack. This immediate position of 75 the die 36 now changes as it rises for a short distance until the co-operating closing die 37 descends through the slot 43 against the tab *b* of the ferrule causing the said tab to be forwardly curved and curled around 80 the strand pack and down upon the tab *c* and in between the upstanding ears *d*. The die 37 remains in pressing contact with the tab *b* while the die 36 again descends in 85 position and against the tab *c*, at which time the dies 36 and 37 are both down against the closed ferrule tabs. The bifurcated bradding die now descends against the upstanding ears of the ferrule. The shape of 90 the extremities of the two prongs of the bradding die is such as to cause the upstanding ears to be bradded down and against the arm *b*. At this period of the operation of the various closing dies the dies 35 and 36 return to their normal position leaving 95 the closing die 37 in position against the ferrule, at which time the punch or turning die 33 is thrust forward against the outstanding horizontal extremity *e* of the tab *b* which turns and curls the extended tab upwardly in a position illustrated in Fig. 5. The die 37 remaining in pressure contact 100 with the arm *b* allows the turning die 33 to come into pressure contact with the extended tab without allowing said tab to be punched back or loosened in its tight position around the strand pack. After the turning die has punched the extended tab upwardly, as illustrated in Fig. 5, the dies 33 and 37 immediately return to their normal 105 position which normal position is illustrated in Fig. 1. The packer arm during the entire operation of the several closing dies has remained in pressure contact with the strand pack. The packer arm now follows the upwardly traveling closing dies into an upwardly limited position away from the strand pack, at which time the mop-head is readily removed from the machine and a new ferrule and strand pack 110 placed therein ready for the closing operation as described. The mop-head is removed from the machine with the extended tab *e* in its upwardly bent position, and is given over to a second manual operation 115 120 where the attendant hammers or presses the said tab over and against and down on top of the folded ears of the ferrule completing the finished mop-head, with a ferrule whose tabs are securely and tightly pressed about 125 130

the strand pack, after which the handle for the mop may be mounted in the ferrule body.

Fig. 7 shows in perspective view the lower extremities of the several closing and bradding dies in position against the ferrule tabs and returning therefrom after said ferrule tabs have been securely folded down.

The invention is presented to include all such modifications and changes in design, form and construction as may properly be constructed to come within the purview of the following claims.

Claims:

1. In an automatic machine for manufacturing mops or for use in connection with securing the yarn or strand pack constituting a mop to a staff or handle, the combination with a frame or base, of a pair of support guide members positioned upon the machine, said support guide members having substantially parallel adjacent faces and of a shape adapted to receive a cylindrical ferrule or similar device having members adapted to be closed around the mop yarn, a plurality of coöperating closing dies, and automatic mechanical operative means provided for the purpose of closing the ferrule.

2. In an automatic machine for the purposes described, the combination with a frame or base of the machine, of a ferrule and ferrule arm receiving and supporting means arranged upon the machine, of a packer device pivotally arranged upon the machine, of a plurality of closing dies carried by the machine, an oscillating arm pivoted upon the machine, of a die or punching tool mounted upon the oscillating arm in a substantial horizontal position and adapted to punch up a ferrule arm, and operative means provided to drive the several closing dies.

3. In an automatic machine for the purposes described, the combination with a frame or base of the machine, of a ferrule receiving and supporting means arranged upon the machine adapted to retain and support a ferrule device with tabs or extremities, of a pivoted packer device carried upon the machine, of a plurality of closing dies carried by the machine, of an oscillating arm pivoted upon the machine, a cam carried by the machine and adapted to impart an oscillating movement to the oscillating arm, a die tool pivotally carried by the oscillating arm, said die tool having an arcuate and pointed working extremity adapted to punch and curl up a ferrule extremity, and operative means provided for driving the several closing dies.

4. In a machine for the purposes described, the combination with a base, of a receiving and supporting means provided for receiving a mop-head fastener device, of a pair of closing dies arranged in operative

position therewith, a bifurcated bradding die adapted to straddle the closing dies and co-operate therewith, a punching or turning die mounted in a horizontal position and adapted to punch the fastener device, and operative means adapted to operate the several die tools.

5. In a machine for the purposes described, the combination with a base, of a pair of ferrule support guide members so arranged upon the base as to form a jaw-like opening for receiving a ferrule, a slot formed in each ferrule support guide members, a plurality of pivotal arm members journaled upon the machine, a plurality of closing dies arranged above the jaw-like opening and carried upon the pivotal arm members adapted to descend upon and against the ferrule closing said ferrule around a yarn pack with which said ferrule had been previously provided.

6. In a machine for the purposes described, the combination with a base, of a pair of ferrule support guide members so arranged upon the base as to form a jaw-like opening for receiving a ferrule, a slot formed in each of the ferrule support members, a cylindrical pillar-post disposed between the jaw-like opening and adapted to receive a ferrule or mop-head fastener device, a pair of coöperating closing dies alined with the ferrule support member adapted to descend into the slots and close the tabs of the ferrule or fastener, a bradding die alined with the slots and adapted to brad over the ears of the ferrule, and a turning die adapted to turn up the extended ferrule tab.

7. In an automatic machine for the purposes described, the combination with a frame, of a shaft journaled upon said frame, a second named shaft journaled upon the frame, a plurality of cams fixed upon the first shaft, a plurality of pivoted arms journaled upon the second named shaft, each cam adapted to subject each respective arm to a pivoted movement, a ferrule receiving and support member disposed upon the frame, a cylindrical pillar-post adapted to receive a ferrule, a pair of coöperating closing tools carried by pivoted arms and mounted above the pillar-post, a bradding die carried by one of the arms and adapted to follow the closing dies downwardly in their movement, an oscillating member pivoted upon the frame, and a turning die carried by said oscillating member, and adapted to move in against the ferrule and turn up an arm of the ferrule.

8. In an automatic machine for the purposes described, a forked receiving member for supporting a ferrule, a pivoted bifurcated packer member so arranged as to pass down over the forked receiving member and pack any matter contained in said forked receiving member, a plurality of coöperating

closing dies pivotally arranged upon the machine, and adapted to be displaced against the ferrule for closing and securing same while the packer member is down.

5. 9. In an automatic machine for the purpose described, the combination with a frame or base, of a receiving and supporting member provided for holding a mop head fastener device, of a plurality of coöperating 10 pivotal arms having a common journal, closing dies carried by the pivotal arms, and means provided to pass said coöperating pivotal arms downwardly against the fastener device.
15. 10. In an automatic machine for the purpose described, the combination with a frame or base, of a receiving and supporting member provided for holding a mop head fastener device, of a plurality of coöperating 20 pivotal arms having a common journal, clos-

ing dies carried by the pivotal arms, and a plurality of cams journaled upon the machine and arranged to operate in connection with each arm.

11. In a machine for automatically clamping about a ferrule a yarn pack intended to be secured to a staff or handle and used as a commercial mop, the combination of a bifurcated receptacle support upon which the ferrule may be placed, a rocker arm journaled upon the machine, and a tool carried by the rocker arm and adapted to close the ferrule around the yarn pack. 25 30

In testimony whereof I affix my signature in the presence of two witnesses.
